UNITED STATES PATENT OFFICE.

WALTER J. WOOD AND THOMAS W. WOOD, OF ATLANTA, GEORGIA.

STOVE-PIPE-CRIMPING MACHINE.

SPECIFICATION forming part of Letters Patent No. 357,883, dated February 15, 1887.

Application filed December 9, 1886. Serial No. 221,098. (No model.)

To all whom it may concern:

Be it known that we, WALTER J. WOOD and THOMAS W. WOOD, citizens of the United States of America, residing at Atlanta, in the county of Fulton and State of Georgia, have invented certain new and useful Improvements in Stove-Pipe-Crimping Machines; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to mechanism for crimping and beading the ends of sheet-metal tubes or cylinders, as well as stove-pipes and the like.

The objects of our invention are, first, to provide mechanism which by a single operation will crimp or bevel one end of a length of pipe in order that it may be easily inserted within the end of another length, and at the same time form an interlocking bead upon the coupled end of two lengths of pipe, thus firmly securing said two lengths; second, to provide such mechanism with adjustable supporting-rollers, whereby the coupled lengths of pipe to which is to be secured the length undergoing operation may be supported in alignment with said length.

The invention consists in novel features of construction and combinations, which will be fully set forth in the ensuing specification, and claimed in the clauses at the close thereof.

In the drawings, Figure 1 is a vertical sectional view of our improved crimping and jointing apparatus. Fig. 2 is an end elevation of the supporting-frame and rollers, and Fig. 3 is a sectional view of a modified form of the crimping and beading apparatus.

Referring to Fig. 1, we provide a suitable framing, preferably of metal, and consisting of a standard, A, and housing A', the latter being secured to the standard in any suitable or preferred manner, and the standard being secured to a suitable working-bench, B, as shown. Within the housing are bearings c for a rotating shaft, C, carrying at its inner end a beveled crimping-roll, C', at its outer end a beading-roll, C", and at a point between

these rolls a plain-surfaced guide-roll, C'. These rolls are preferably secured upon the shaft C by set-screws or other equivalent means, in order that they may be adjusted longitudinally upon the shaft. The housing is also provided with bearings d d', in which is journaled a shaft, D, provided with beveling-roll D' and beading-roll D" and a plain-faced guide-roll, D'. One of these shafts—say C—is extended at the inner end through the housing to receive a hand-crank, E, or other operating means. These shafts are provided with intermeshing pinions c' d', and the bearings of the shaft D are mounted in guides in the housing, to permit the shafts being moved asunder for the insertion of a pipe-length, F, between the rollers thereon. A stop, e, is adjustably secured at a little distance from the inner end of the beveling-rolls C' and D', and while we have shown this stop as mounted upon the shaft D, it will be understood that it may be secured to the housing, as its only purpose is to stop a length of pipe at a proper position with relation to the respective rolls.

To move the shafts C and D asunder for the reception of the length of pipe, we have interposed springs G between the bearings of said shafts, which springs are compressed to bring the shafts and their rollers into operative position by means of a screw and follower, G'; but it will be understood that a screw or lever may be used to move the bearings d d' in both directions without departing from the principles of our invention.

The supporting-rolls H are arranged in pairs upon shafts h, arranged parallel to each other and journaled in bearings secured to the upper ends of standards i, fixed to a supporting-bracket, I. The inner end of this bracket I is provided with a clamp, I', by which the bracket may be adjustably secured upon the standard A, said standard being provided with a scale to indicate the position to which said bracket should be adjusted to support pipes of different diameters.

In operation, a length of pipe, F, is to be inserted between the rolls upon the shafts and the movable shaft adjusted for operation. Upon rotating the shafts the extreme end of the length of pipe will be beveled or crimped inwardly, so that it may be the more readily

inserted in another length of pipe. The shafts and rolls are then moved asunder, the length of pipe F removed and the beveled end inserted within the end of another length of pipe, 5 F', when said other length should be inserted between the rolls, and undergo the operation heretofore described with relation to the length F. Before this, however, the beveling-rolls C' D' and beading-rolls C'' D'' have been 10 so adjusted with relation to each other that while said beveling or crimping rolls C' D' operate to crimp the end of the pipe-length F' the beading-rolls will operate upon the lapped ends of lengths F and F' and form an interlocking bead therein, whereby they will be secured firmly together. As this operation is 15 repeated with additional pipe-lengths, the pipe-lengths which have been secured together are supported and guided by the supporting- 20 rolls H.

Should it be desired to disconnect two lengths of pipe which have been united by the beading-rolls, these rolls may be removed from the shafts and the bead passed between the plain-surfaced rolls C' D'', the action of which will 25 be to flatten out the bead, so that the lengths may be withdrawn from each other.

It will of course be understood that this machine may be used for crimping and beading 30 stove-pipes for the trade without joining them together. In this case the bead formed upon the pipe-length would act simply as a stop to prevent two lengths of pipe from being overlapped too far.

In the modification shown in Fig. 3 the movable shaft D is mounted at its inner end in a bearing, d, which is pivoted in the housing, a spring, G, being interposed between the shafts C and D, tending to force said shafts asunder, and a screw and follower being located near the outer end of a movable shaft. The operation of the machine, however, is unchanged. 35 40

We claim—

1. The combination, with the standard and 45 housing, of a shaft mounted in fixed bearings, a shaft mounted in a movable bearing, said shafts being provided with smoothing, crimping, and beading rolls and with intermeshing pinions, a spring interposed between said 50 shafts for moving them asunder, and a screw or follower to compress said spring and move the rolls into operative position.

2. In a stove-pipe beading and crimping machine, the combination, with the standard 55 provided with a scale, of a bracket provided with supporting-rolls arranged in pairs, and with a clamp to secure said bracket on the standard.

In testimony whereof we affix our signatures to in presence of two witnesses.
